DES. 2219

Charles Williams of Manchester, N. H.

Letter's Patent No. 2219 Dated Nov. 7, 1865.

Design for a Parlor Stove.

The schedule referred to in these Letters Patent and making part of the same

It all Persons to whom these Presents shall come.

Be it known that I, Charles Williams of Manchester, in the County of Hillsboro and State of New Hampshire have invented or produced a New and Ornamental Design for a Parlor Stove, such Design being duly represented in the accompanying drawings marked Figures 1. and 2. the former of which exhibits a perspective front side view, and the latter a perspective end elevation of it.

The Stove consists of a cast metal frame containing panels of slate. The end elevation exhibits a smoke pipe applied to the back part of the stove, such pipe constituting no part of the Design.

In the drawings a, a, denotes the panels. e, is the former, b, the door. ~~and c, its frame.~~

A fender or foot rest is also shown as applied to the frame.

The ornamental character of the frame constitutes the Design, such Design including the door and its frame, the whole being as exhibited in the drawings.

What I claimed my invention or production is the design as represented in the above mentioned drawings, and as hereinafter set forth.

Witnessed,

Re H. Eddy
